UNITED STATES PATENT OFFICE.

WILLIAM C. EDGE, OF NEWARK, NEW JERSEY.

DESIGN FOR A CHAIN.

SPECIFICATION forming part of Design No. 31,221, dated July 18, 1899.

Application filed March 17, 1899. Serial No. 709,553. Term of patent 7 years.

To all whom it may concern:

Be it known that I, WILLIAM C. EDGE, a citizen of the United States, residing at Newark, in the county of Essex and State of New Jersey, have invented and produced a new and original Design for Chains; and I do hereby declare the following to be a full, clear, and exact description of the invention, such as will enable others skilled in the art to which it appertains to make and use the same, reference being had to the accompanying drawings, and to letters of reference marked thereon, which form a part of this specification. Figure 1 of the drawings shows a plan of the newly-designed chain, and Fig. 2 is an edge view of the same.

As shown in the drawings, the leading or material feature of the design consists in two series of links, the links of one series cross-

ing those of the other at an angle and each link being shaped in resemblance to two links lying parallel one to the other.

In the drawings, *a a a* indicate one series of links, and *b b b* the other series of links crossing those of the first series at an angle, as shown in side view. Each link is shaped in edge view in resemblance to two links *c c*, placed side by side.

What I claim as new is—

The design for a chain herein shown and described.

In testimony that I claim the foregoing I have hereunto set my hand this 8th day of March, 1899.

WILLIAM C. EDGE.
